UNITED STATES PATENT OFFICE.

OLIVER WARREN JOHNSON, OF BUCYRUS, OHIO.

RAILWAY-GATE.

SPECIFICATION forming part of Letters Patent No. 450,235, dated April 14, 1891.

Application filed July 6, 1889. Serial No. 316,677. (No model.)

To all whom it may concern:

Be it known that I, OLIVER WARREN JOHNSON, a citizen of the United States, residing at Bucyrus, in the county of Crawford and State 5 of Ohio, have invented certain new and useful Improvements in Railway-Gates; and I do declare the following to be a full, clear, and exact description of the invention, such as will enable others skilled in the art to which 10 it appertains to make and use the same, reference being had to the accompanying drawings, and to the letters and figures of reference marked thereon, which form a part of this specification.

15 This invention relates to railroad-gates and means for operating the same from an approaching train.

The improvement consists of the novel features and the peculiar construction and combination of the parts, which will be hereinafter more fully described and claimed, and which are shown in the annexed drawings, in which—

Figure 1 is a side elevation showing the gate 25 arranged at right angles to the track. Fig. 2 is a side elevation showing the gate arranged parallel with the track. Fig. 3 is a diagrammatical view. Fig. 4 is a perspective view of the shaft that carries the trip-arms. Fig. 5 shows a side 30 view of the trip-arms, a front view of the casting to which the trip-arms are secured, and a side view of the pin for connecting the trip-arm with the casting. Fig. 6 is a perspective view of the bearing-block, showing the retaining-springs; Fig. 7, a side view of the trip-arm; Fig. 8, a detail view of the catch for holding the gate shut. Fig. 9 is a detail view, partly in section, of the upper part of the post which supports the gate and the warning-board. Fig. 10 is a front view of the shaft 35 that carries the warning-board trips. Fig. 11 is an end view of the shaft shown in Fig. 12. Fig. 12 is a side view of the warning-board sheave and stem and a perspective view of the 40 eyebolt to which the spring that returns the warning-board to a normal position is attached. Fig. 13 is a side and front view of the stop-casting and a side view of the double hook which secures the spring and cable to 45 the warning-board sheave. Fig. 14 is a cross-section of the case that incloses the warning-board-operating devices. Fig. 15 is a side

view of the gate-hinge rod. Fig. 16 is a side view of the double sheave and frame. Fig. 17 is a side view of the single pulleys and frame. Fig. 18 is a detail view of the casting which supports the trip-arm. Fig. 19 is a detail view of the washer having the hexagonal bushing that enters opening in side of trip-arm supports.

55 My description and drawings represent an east-and-west railroad with north-and-south wagon-road crossing it. This will be remembered by the reader and this description will have the same bearing on any road running 60 in any direction of the compass.

These gates are for the purpose of keeping people, teams, and stock off the track when trains are approaching and passing by. They are situated substantially as hereinafter described. There may be under this head two classes or kinds of railroad-gates, their difference consisting of the following: One class has but two gates, while the other has four. The apparatus and connections are the same 70 for both classes, except that the system of four gates has two swinging cables more than the system comprising but two gates, which gates are differently disposed from the four-gate system, as hereinafter described.

80 The gates, four in number, are designated on the drawings by the figures 1 1^a, and are made of wood, after the manner of any swinging gate, being hung on posts 2 by iron rods and eyebolts 18, which hereinafter will be 85 more particularly described. These gates are set in two positions. Either one can be successfully used. In one position, that shown in Fig. 1, the gates answer two purposes: first, they keep when shut stock and people from 90 going up or down the track, thus making a cattle-guard unnecessary, and when open they keep stock, people, and teams off the track until coming trains are passed.

95 The gates are disposed two 1 1^a on the north side of the track (one on each side of the wagon-road) and two 1^a 1^a on the south side, (one on each side of wagon-road same as the gates on north side of track,) and are arranged to swing from center of track to center of 100 wagon-road. Thus the four gates form a square. These gates are hung on posts 2, as stated before, and are long enough to reach from center of track or tracks (in case there

be two or more) so far from the track that a passing train will not strike them when open to railroad. The other position of the gates is as shown in Fig. 2, in which they are set two 5 on each side of the track at such a distance therefrom that the ends of the gates on opposite sides of the track will not meet in center thereof.

Having the gates arranged as first described 10 does away with the cattle-guard and guards the wagon-road at the same time, while arranging them as last described guards the wagon-road only.

Fig. 1 represents the gates meeting in center of track. Fig. 2 shows gates set off from the track, and the only difference in the mechanism for operating the gates consists in lengthening the swinging cables for the gates shown in Fig. 2. Fig. 2 also represents the 15 pole-gate, which can be used in place of the panel-gates in a cold climate where there is plenty of snow. It will not be hindered by snow-banks as quick as the others will, the operating mechanism and connections being 20 the same in each instance.

Turn-rod 3 has its upper end bent at a sharp angle and inserted in and through the post end of the gate, and a nut 3' is screwed thereon. To the lower end of two of the rods 3, which 25 correspond with the west pair of gates on opposite sides of the road, is keyed the cable-sheave 4, a cast-iron cable-wheel three-fourths of an inch thick at its rim, eight inches in diameter, and one and one-half 30 inch in thickness at the hub. There are six of these sheaves all the same size and numbered as follows: 4 4, 10 10, and 15 15. The position of each will be more particularly described hereinafter. At bottom end 35 of the same turn-rods 3, which extend into the ground far enough to enter the trough or box inclosing the cables 14 (which run under the wagon-road to the sheave 15 on the turn-posts of the east pair of gates) are keyed the cable-sheaves 10, before described. Said sheaves 40 10 have fastened to them the cables 14. These cables are ordinary cables three-eighths of an inch in thickness and extend from sheaves 10 under the road in boxes or troughs to 45 sheaves 15 and are crossed, and each has two turn-buckles 7 in it to tighten or loosen it, as desired. The cable-sheaves are keyed on the turn-rods 3 of the east pair of gates and are used for the purpose of turning the rods 3 to 50 open or shut the said east pair of gates by means of the cables 14. Cables 5 are common one-half inch cables connecting sheaves 4 with the main cable-sheave 13, and the one on the south side of the track (see Fig. 3) is 55 not crossed. These are the cables that are lengthened and shortened by having the gates set off from or near to the railroad. These cables have two turn-buckles 7 on each one to tighten or loosen, as may be desired, and 60 two spiral springs 6. These springs are strong and flexible, capable of bearing a sudden strain. The object of having these springs

in these cables is this: When the train strikes the trips 27 and turns them it is done so quickly that something would break if everything were 70 tightly connected; but, as these springs are in the cables, one on each side of the cable, (four in all) to give when pulled from either way, the trips can be turned and caught almost before the gates move, and no sudden jar will be felt by the gate. The swinging cable-sheave 13 has two one-half-inch grooves, and may be cast with a corresponding double-grooved sheave 17 or secured to the shaft on which said sheave 17 is keyed. Said sheaves 80 17 and 13 are inclosed in a kind of clamp box or casing 19, which is composed of two pieces of iron one inch thick, four inches wide, and twenty-one inches long, which are shaped as shown most plainly in Fig. 16, and are bolted 85 together at the ends. Holes are drilled in the center of the plates to receive the journals of the sheaves 17 and 13. These sheaves 17 and 13, inclosed in casing 19, are placed in the center of the track between the gate-posts, as 90 shown in Figs. 1 and 3. Swinging cables 5 are connected to sheave 13 and main cables 11 are connected to sheave 17. Main cables 11 are five-eighths-inch cables, with two turn-buckles in each to tighten or loosen them, as 95 desired, and connect the gates to the trips by being fastened to sheave 17 at one end and to trip-shaft sheaves 24 at the other end.

Gate latch or lock 9 consists of three pieces of iron A, B, and C. The latch A is elbow-shaped and its top arm is one and one-half inch thick at its catch end, and has a square notch cut in it to hook over catch D and keep the gate from coming too far around or swinging back again. The vertical arm of the 105 latch tapers down to three-fourths of an inch square and the cable 8 is fastened to it. C is the plate holding catch D and is screwed on the butt-end of the gate near bottom. E is a pin which acts as a rest or stop for latch A, 110 keeping the spiral spring F from pulling said latch A too far down. B is the plate screwed or bolted on the gate-post opposite to catch C, and has a pin G, on which latch A is mounted.

27 represents the trip-arms, which are crescent-shaped pieces of wrought-iron three-fourths of an inch thick, two and one-half inches wide, and seven and one-half or eight inches long. The object of having the trip crescent-shaped is to allow the tripper on the engine to force the cast arm 28 down into the catch-springs 29 (on journal-bearing 26.) As the tripper reaches only about to a level with the rail, the crook in arm 27 is necessary 125 to accomplish that end, (to make casting 28 catch in spring 29.) The cast-iron arm 28 is to hold arm 27 in proper position, and the spiral spring 32 is slipped into place and the washer 31 adjusted and the pin 30 put through 130 all and fastened. The washer 31 has a hexagon bushing or cushion that fits in the hole on arm 28, the purpose being to keep the washer from turning when arm 27 is pushed

the wrong way and the spring 32 is strained to bring it back again, as one end of the spring is fastened to said washer. The object of having the arm jointed is this: After an engine 5 has turned one trip down, of course the other one stands up. In case there should be an unusually low oil-box or something broken about the train, and it should hit the arm standing up, instead of breaking it will bend 10 forward when struck, and spring 32 will throw it back in place after the obstruction passes by. These trip-arms are put on the end of a shaft called the "trip-shaft" 23. There are two arms 27, last described, to each trip-shaft 15 23. Said shaft is three feet longer than the space between the railroad-rails and is placed under the rails and up against them. Next to the trip-arm is a wrought-iron box 26, in the center of which is formed the bearing for 20 shaft 23 to work in. Two steel springs 29, shaped as shown, are fastened to said box, one on each side of the bearing, to hold the arms 27 against all the strain the gates will put on them, and yet when the tripper on the 25 engine strikes the arm 27 the arm 28 will pull out of spring 29 on one side and the other arm will become engaged with the other spring 29. As there are eight of these springs and four used at a time, they will hold the gates 30 solid against any ordinary storm, and as the cables are firmly connected between the trips when one pair of trips is pressed forward the other pair of trips will be disengaged from one set of springs 29 and pressed forward and 35 engaged with the springs 29 on the other side of the box. The object of having these springs is this: The trains run so fast that the act of striking the trips and passing them is almost instantaneous, and as the gates are protected by the spring 6 from a sudden jerk said 40 gates will not move near so rapidly as the trips. Hence if the trips were not caught and held when pressed down they would fly back. The springs 29 prevent the trips 28 45 from moving back until positively operated. As these springs 29 are not made with sharp angles for catches, they will allow the trip-arms 28 to pull out when sufficient force is applied.

50 Next to the cable-sheave 24 on shaft 23 is placed box or bearing 25, which is identical with boxes 26 without the springs. Said box 25 is inverted and is secured to the ties and is designed to keep shaft 23 from springing 55 in the center.

Trips 27 are placed some distance from the gates both ways, (east and west,) say one-quarter or one-half mile, or farther, if desired. Fifty or one hundred yards or farther 60 beyond the trips 27 in the direction away from the gates is placed the warning-board trip 47. Trip-arm 47 is weighted at its lower end to balance and hold the arm in a vertical position. The cable 35 is fastened to the bottom 65 of the trips 47 and extends to the gates on the intervening ties through pulleys that are

placed at intervals. When at the gate they pass through double-cable pulley 12 and unite in one strand, said strand continues onto gate-post through pulleys 49 into casing 34 and around sheave 37 on the side toward which the warning-board swings and is fastened in hook 38.

The warning-board 33 is five or six feet in 75 length, more or less, ten or twelve inches wide, and one inch thick, and is inserted in a slot in the top end of the shaft 36. On the lower end of shaft 36 is keyed sheave 37, with a hook 38 screwed upon it to hold or fasten cable 35 80 and spiral spring 42 thereto. The hook 38 is double-ended, and when spring 42 and cable 35 are put in the hooked ends of 38 these ends are closed or pressed down to the body or plate of the hook, thus holding the spring 85 and cable firmly.

The spiral spring 42 is the means for returning the cable-sheave 37 to place when the gates are thrown around to cross the wagon-road. The end of the gate strikes the trip-lever 43 and releases the sheave 37, and then spring 42 pulls the warning-board back to its place by means of sheave 37 and shaft 36, before specified. Said spring 42 is fastened at its outer end by eyebolt 39 to the casing 34. 95

The spring 44 is designed to hold the lever 43 in engagement with the teeth on the sheave 37, and is fastened at one end to lever 43 and at its other end to a plate and lug 45.

Trip 47 should be set far enough up the 100 track to admit of persons crossing the track after the turning of the warning-board before the gates close. Said train next strikes the trip 27, presses down the arm standing up, and fastens it in springs 29. Now the cable 105 11 is double, (as all the cables are except cable 35 of the warning-board,) one strand is on the south side of the main cable-sheave 17 and one is on the north side of said sheave. The cable-strand on the south side is run on the 110 under side of cable-sheave 24 of the trip on the west side of the gates, and the north cable-strand is run on the top side of the sheave, each one being fastened to said sheaves 17 and 24, as before stated. The east trip-shaft 115 sheave 24 has its cable 11 reversely arranged. Thus the south cable-strand running east from the south side of sheave 17 is run over the top of trip-shaft sheave 24 and the north cable-strand runs from said sheave to and 120 under sheave 24. They both are fastened on the sheaves, as specified before. When either set of trips is turned to open the gates, the arrangement described causes the eastern and western gates to move in opposite directions. 125

An approaching train striking one of the trips 47 pushes it toward the gates, thus drawing the cable 35 and bringing the warning-board across the wagon-road. The lever 43 slips into one of the notches X when the 130 strain is gone and holds the warning-board until the gates swing around and the butt-ends of the gates strike the lower end of lever 43 and push it in, thus releasing it from the

sheave 37, which is instantly drawn back to its proper place by means of the spiral spring 42.

Obviously in adapting my invention to single and double tracks and to tracks on the same and different levels changes in mechanical construction and arrangement of parts will be necessary. However, these changes are such as will suggest themselves to the skilled mechanic and will not alter the scope and spirit of the invention.

Having thus described my invention, what I claim, and desire to secure by Letters Patent, is—

15 1. In a railroad-gate, the combination of the gates adapted to swing in a horizontal plane, the rods 3, the sheaves 4, attached to the rods 3, the cables 5, having springs 6 and turn-buckles 7, the sheaves 17 and 13, the cable 11, 20 the shaft 23, having the sheave 24, around which the cable 11 passes, and the trips 27 on the ends of the shaft 23, substantially as described.

2. The combination, with the gate-post, the 25 gate hinged thereto, and the cable 5 for operating the gate, of the stop D on the gate, the latch 9, pivoted to the gate-post and adapted to engage with the stop D, the stop E for limiting the movement of latch 9, and 30 connection 8 between latch 9 and cable 5, substantially as and for the purpose described.

3. The combination, with the posts 22, the 35 gates, the rods 33, forming a hinge-connection between the gates and said posts, and the cable 5, having connection with the said rods 33 to open the gates simultaneously, of the stops D on the gates and the pivoted

latches 99 on said posts for holding the gates closed, and the connections 88 between the ends of cable 5 and the latches 99, whereby 40 the latches will be operated to release the gates before the said gates are opened, substantially as described.

4. The combination, with the railroad-gates, the shaft 23, and connections between the 45 gates and the shaft 23, of the trip-arms 27 and the spring-catches 29, substantially as and for the purpose described.

5. The combination, with the gates, the shaft 23, and connections between the gates 50 and shaft, substantially as described, of the casting 28, the curved trip-arms 27, disposed at right angles to one another and curving inward, the pins 30, pivotally connecting the trip-arms with the casting, the springs 32, 55 mounted on the pins and adapted to return the said arms to an operative position, and the spring-catches 29, substantially as set forth.

6. The combination, with the gates, the 60 shaft 23, and connections between the gates and the shaft, of the casting 28, the trip-arm 27, pin 30, washer 31, placed on the pin and adapted to be fitted in the casting 28, the spring 32 between the trip-arm and washer, 65 and the spring-catches 29, substantially as and for the purpose described.

In testimony whereof I affix my signature in presence of two witnesses.

OLIVER WARREN JOHNSON.
